UNITED STATES PATENT OFFICE.

SILAS T. MARLETTE, OF BUFFALO, NEW YORK, ASSIGNOR OF ONE-HALF TO
THOMAS G. O'BRIEN, OF SAME PLACE.

HAME-FASTENER.

SPECIFICATION forming part of Letters Patent No. 665,246, dated January 1, 1901.

Application filed August 2, 1900. Serial No. 25,661. (No model.)

To all whom it may concern:

Be it known that I, SILAS T. MARLETTE, of Buffalo, in the county of Erie and State of New York, have invented a new and useful Improvement in Hame-Fasteners, of which the following is a specification.

My invention is in the nature of an improved hame-fastener designed for quickly, securely, and conveniently connecting the lower ends of the hame-sections about the collar with a tightening action and adapted to be used in connection with any of the ordinary forms of hames.

It consists in the peculiar construction and arrangement of the fastener, reference being had to the accompanying drawings, in which—

Figure 1 shows a side view applied to the hames and indicating in dotted lines the opened position. Fig. 2 is a detail in side view of the locking parts opened, and Fig. 3 is a view in section of them closed and locked.

A A' are the two sections of the hames, having at their lower ends the usual iron loops into which the hame-fastener hooks are inserted. The hame-fastener consists of the part B, having at one end the hook b. The part B is jointed at one end upon a pin 1 to the end of section C, which normally lies under B and is recessed longitudinally to allow the part B to fold into something like the blade of a knife into its handle, B corresponding to the blade, and C its handle.

D is the third section, which carries a jointed hook d, that hooks into the loop of the other hame. This part D has a narrow shank portion that fits into a longitudinal recess on the under side of the part C and is jointed to the part C at a point 2 between the joint l of the members B and C and the opposite end of the part C. The three parts B C D when thus jointed are capable of being opened, as shown in dotted lines, and when thus opened the two hooks b and d, which connect with the hames, are projected away from each other to loosen the hames, and when drawn together again and closed, as shown in full lines, the hooks b and d are drawn together and the hames tightened upon the collar.

To hold the parts B and C together in the closed position, special locking devices are em-

ployed, which I will now proceed to describe. The part C has a curved seat at its end which lies under the curved hook b and is provided also on the under side with two lugs c and c' 55 to give a hold for the thumb and forefinger in opening the parts, as hereinafter described. This curved seat of the part C is formed in two branches or is made forked, with two branches connected by a cross-pin f, and the hook b is also made with a slot in its lower portion. On the branches of the fork of the part C is erected a loop or keeper e, whose ends are fixed rigidly to the branches of the forked seat and whose loop portion projects 65 upwardly through the slot of the hook b of the part B.

In the slot of the hook b there is fulcrumed on a pin g a locking-latch E, one of whose ends projects beyond the hook b and through 70 the branches of the fork of part C, so as to be easily reached to form a finger-latch. The other end has an upwardly-curved end which has two seats d and d'. Into the seat d' there lies the end of a wire spring h, which is 75 wound around the pin g, which tends to hold the inner end of the latch down and the outer end up. The other seat d is adapted to receive the loop of the keeper e and hold the two parts B and C locked together. 80

When the device is open and C is closed up under B, the loop or keeper e strikes the under side of the inner end of latch E, deflecting the latter until the loop passes its end, and then the latch springs back under the loop, 85 effectually locking B and C together. To open B and C, the outer end of latch E is depressed with the finger until its inner end is pulled from beneath the loop, as seen in dotted lines in Fig. 3, and then C may be pulled 90 down to the dotted position shown in Fig. 1 by means of the thumb and forefinger applied to the two lugs c and c'.

I am aware that a hame-fastener having three jointed sections adapted to draw the 95 ends together when folded is not broadly new, and I do not claim this general principle, but only my improved construction and the locking devices herein shown and described.

A distinguishing feature of my invention 100 is to be found in the special construction of the intermediate section C in relation to the

- parts B and D. The section C is made wide enough and deep enough to inclose the shanks of both B and D, being recessed at the upper side to receive the shank of B and on the under side to receive the shank of D, while the concave seat of C fits closely up against the convex side of the hook of the section B, which hook is made of larger size, opens upwardly, and contains the locking devices.
- Having thus described my invention, what I claim as new, and desire to secure by Letters Patent, is—
1. A hame-fastener comprising a section B formed with a hooked end opening upwardly, a hooked section D, an intermediate section C made wide enough to receive the shanks of both the sections B and D, recessed on the upper side to receive the shank of section B and jointed to it at one end, and having at the other end a curved seat whose concave side fits the convex side of the hook of section B, said section C being also recessed on its under side to receive the shank of section D and being jointed to it at a point near the middle of the said section C, and locking devices connecting the hooked end of B to the curved seat of C substantially as and for the purpose described.
  2. A three-part hame-fastener, one of the end sections being made with a large upturned hook opening upwardly and containing lock-

ing devices, and the middle section being formed with a concave seat fitting up against the lower convex side of said hook and coöperating with the locking devices substantially as described.

3. In a hame-fastener, the combination of the hooked section B having a slot in the lower portion of the hook, and a spring-actuated locking-latch in the slot, and a subjacent section C having a locking-keeper attached to the same and projecting up through the slot in the hook to engage with the locking-latch substantially as described.

4. In a hame-fastener, the combination of the hooked section B having a slot in the lower portion of the hook, and a spring-actuated locking-latch in it, and a subjacent section C having bifurcated curved ends and a loop-shaped keeper rigidly attached to the same and projecting up through the slot in the hook to engagement with the locking-latch substantially as and for the purpose described.

In testimony whereof I have signed my name to this specification in the presence of two subscribing witnesses.
